UNITED STATES PATENT OFFICE.

ALBERT WANNER, JR., OF HOBOKEN, NEW JERSEY.

DESIGN FOR A CHAIR-BACK.

SPECIFICATION forming part of Design No. 35,901, dated May 6, 1902.

Application filed March 20, 1902. Serial No. 99,217. Term of patent 14 years.

To all whom it may concern:

Be it known that I, ALBERT WANNER, Jr., a citizen of the United States, and a resident of Hoboken, in the county of Hudson and State of New Jersey, have invented and produced a new and original Design for a Chair-Back, of which the following is a full, clear, and exact description.

Reference is to be had to the accompanying drawings, forming a part of this specification, in which—

Figure 1 is an elevation of a chair-back, showing my design; and Fig. 2 is a plan view.

The design in its entirety consists of a marginal frame and the internal members having the peculiar configuration shown by the drawings. Said marginal frame has the side portions $a a'$ and a top portion a^2 . The internal members $b c$ are curved downwardly from the side portions of the frame and are then curved upwardly, the members crossing or overlapping one another. The upwardly-extending portions $d e$ of the members are curved outwardly upon themselves and into the scrolls

$f g$. The top edges of the scrolls touch the top portion a^2 of the marginal frame and the terminals of the scrolls touch the upwardly-extending portions $d e$ of said internal members.

h is the chair-seat, and $i i'$ are the side arms.

The leading feature of my design is the internal members crossing each other and having their lower ends touching the side portions of a marginal frame and their upper portions curved outwardly upon themselves.

Having thus described my invention, I claim as new and desire to secure by Letters Patent—

The design for a chair-back as herein shown and described.

In testimony whereof I have signed my name to this specification in the presence of two subscribing witnesses.

ALBERT WANNER, JR.
